UNITED STATES PATENT OFFICE.

WILLIAM H. KING, OF NEWARK, NEW JERSEY.

CIGAR OR CIGARETTE HOLDER.

SPECIFICATION forming part of Letters Patent No. 645,399, dated March 13, 1900.

Application filed November 17, 1899. Serial No. 737,329. (No model.)

To all whom it may concern:

Be it known that I, WILLIAM H. KING, a citizen of the United States, residing at Newark, in the county of Essex and State of New Jersey, have invented certain new and useful Improvements in Cigar or Cigarette Holders; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

10 The objects of this invention are to provide a cigar or cigarette holder of cheap construction and composed of separable parts, to enable different mouthpieces to be used in the same holder and different materials to be used 15 for different portions of the device, to obtain greater compactness and to reduce the size and cost of the case for containing said holder, to produce a more ornamental and pleasing appearance, and to secure other advantages 20 and results, some of which may be referred 25 to hereinafter in connection with the description of the working parts.

The invention consists in the improved cigar or cigarette holder herein described and 30 in the arrangements and combinations of parts of the same, all substantially as will be hereinafter set forth and finally embraced in the clauses of the claim.

Referring to the accompanying drawings, 35 in which like letters of reference indicate corresponding parts in each of the several views, Figure 1 is a side view in perspective of my improved holder. Fig. 2 is a central longitudinal section of the same on an enlarged 40 scale. Fig. 3 is a central sectional view with the parts in telescoped position, and Fig. 4 is a similar section showing a modification of construction.

In said drawings, *a* indicates the mouthpiece, which may be formed of amber, meerschaum, or any other suitable material. Said mouthpiece is perforated, as at *a'*, to provide a smoke-passage, and the forward end is preferably recessed concavely, as at *a''*, while the 45 rear end is provided with a head *a'''* to be grasped by the mouth.

b b indicate tubular sections, preferably

formed of sheet metal, and any number of which may be employed in a given holder. In the drawings I have shown two such sections in connection with a mouthpiece; but the lengths might be varied, so that either more or less would be required. Said sections *b* are preferably made tapering or flaring toward the forward end and are arranged 55 one within another in a telescopic manner, so as to move longitudinally with respect to one another in the line of the axis of the holder. This enables the parts of the holder to be finished separately in the process of manufacture and to be made different from one another, if desired. The parts may also be separated for cleaning, and, furthermore, greater compactness is secured, so that a smaller case 60 will contain the cigar-holder when not in use. 70

When the sections are made flaring, as shown, the larger end of any inner section is preferably larger than the smaller end of the inclosing outer section, and thus a complete separation of the sections is prevented when 75 the holder is expanded into operative form. Other stop means may be used without departing from the spirit and scope of my invention.

The mouthpiece *a* is made flaring at its forward end, as at *a''*, and said flaring end of the 80 mouthpiece lies in the rear section *b* and is of a slightly-larger diameter than the smaller rear end of the section. This prevents rearward withdrawal of the mouthpiece; but said mouthpiece can be removed forwardly 85 through the sections *b*, and thus entirely detached from the other parts of the holder. Mouthpieces may thus be changed in the same holder as often as desired.

When it is desired to prevent a separation 90 or falling apart of the sections upon closing the holder telescopically, a stop *d* is provided at the forward or larger end of the outer section, which stop may either be permanently soldered upon the section or separably connected thereto by screwing or like suitable means. Said stop *d* is of annular form and concavely curved in cross-section, providing a middle *d'* to abut against the edge of the section *b* and having an outer ornamental 100 flange *d''* lying against the outside of the section *b* and an inner flange *d'''* projecting rearwardly into the tubular section *b*. Said inner flange *d'''* stands away from the inner

wall of the tubular section and forms therewith an annular pocket e , which receives the ends of the inner sections as they are telescoped. The flange d^3 , forming this pocket, 5 may, if desired, project sufficiently far toward the axial line of the holder to also serve as a stop for the mouthpiece, as shown in Fig. 4, the whole stop d in this case being made separable or so that it can be detached from the 10 other parts, if desired.

Having thus described the invention, what I claim as new is—

1. A cigar-holder comprising a mouthpiece, tubular sections adapted to slide telescopic- 15 ally upon one another, and stops limiting said sliding, substantially as set forth.

2. A cigar-holder comprising telescopic sec- 15 tions arranged one within another and a

mouthpiece lying in the inner section, the rear end of each section being formed to prevent the 20 complete withdrawal of the inclosed member, and a stop at the forward end of the outer section, substantially as set forth.

3. A cigar-holder comprising a mouthpiece flaring at its end and a flaring tubular sec- 25 tion, the flaring end of the mouthpiece lying in the tubular section and being of greater diameter than the smaller end of said section, substantially as set forth.

In testimony that I claim the foregoing I have hereunto set my hand this 9th day of November, 1899.

WILLIAM H. KING.
